UNITED STATES PATENT OFFICE

SVEN A. PILBLAD, OF BOSTON, MASSACHUSETTS, ASSIGNOR, BY MESNE ASSIGNMENTS,
TO PETERS PATENTS CORPORATION, OF BOSTON, MASSACHUSETTS, A CORPORATION

METHOD OF MAKING FINGER RINGS

Original application filed June 16, 1930, Serial No. 461,393. Divided and this application filed May 13, 1931. Serial No. 537,036.

This application is a division of one filed by me on June 16, 1930, Serial No. 461,393.

This invention relates to a method for 5 making finger rings particularly stone protected rings.

One of the objects of my new method is to make a finger ring in which the stone is protected, that is, not directly exposed, in a 10 simple and inexpensive way.

The foregoing and other objects which will appear as the nature of the invention is better understood, may be accomplished by a construction, combination and arrangement 15 of parts such as is disclosed by the drawing. The nature of the invention is such as to render it susceptible to various changes and modifications, and, therefore, I am not to be limited to the construction disclosed by the 20 drawing; but am entitled to all such changes therefrom as fall within the scope of my claims.

In the drawing:

Figures 1, 2, 3, 4 and 5 are perspective 25 views of the design member, stone, filler piece, holding device and ring band respectively.

Figure 6 is a cross-sectional view of a completely assembled ring just before the upper portion of the holding device is rolled over 30 onto the design member.

Figure 7 is a cross-sectional view of a finished ring.

As illustrated the band 12 of my ring is formed with a flat base portion 13 on which 35 rests the ornamental parts which constitute the head of the ring. An outside frame or holding device 14, the sides of which slant inwardly as shown, is soldered or otherwise permanently united to said base, the upper 40 portion 15 of which is cut out on the inside so that it may be rolled over easily as later described. Inside said frame 14 is preferably provided a filler piece 16 of some suitable material such as fiber, cardboard, or a 45 metal which has slight springing qualities. On said filler piece 16 rests an onyx or other kind of ornamental stone 17 and on top of said onyx 17 rests a top piece or design member 18, the outside edges of which are beveled 50 inwardly towards the top as shown at 19.

When all of the parts are assembled they are permanently held together by rolling over 55 said upper portion 15 of the outside frame 14 so that it rests against the beveled outside edges 19 of said design member 18 as shown in Figure 7 of the drawing. The design member 18 is flush with the top surface of the outside frame 14 which gives the ring a finished appearance.

On account of the fact that the onyx or 60 other stones will vary somewhat in thickness it has been found preferable to use said 65 filler piece 16 so that the stone will not be loose in its mounting, although this filler piece is not absolutely essential, as stones of the proper thickness can be secured and used.

What I claim is:

1. The method of making a finger ring comprising forming a band with a flat base portion, forming a hollow holding device and 70 soldering said device on said base portion, placing a stone within said device, placing a design member upon said stone, and rolling over the upper portion of said device against 75 said design member.

2. The method of forming a finger ring comprising forming a band with a flat base portion, forming a hollow holding device, cutting out part of the upper portion of said 80 device, soldering said device on said base portion, placing a stone within said device, placing a design member within said device above 85 said stone, and rolling over the upper portion of said device against said design member.

SVEN A. PILBLAD.
